COMBUSTION TYPE AIR HEATER FOR
HOUSE TRAILERS

Deward B. Hohnstein, Denver, Colo.

Application January 17, 1947, Serial No. 722,496

4 Claims. (Cl. 126—110)

1

This invention relates to improvements in gas heaters and has reference more particularly to heaters designed with special reference to the heating of automobile trailers of the house type, but which can, of course, be employed wherever a small heating device is desired.

In the heating of trailers, it is quite important that the size of the heating apparatus shall be small as practicable and at the same time it must be so constructed that it operates at a high efficiency.

It is the object of this invention to produce a heater of a comparatively small size that can be operated by means of liquid fuel or bottled gas.

It is an object of this invention to produce a heater of such construction that the heated gas and gases of combustion that pass from the combustion chamber will travel through a heat radiating or transfer chamber in opposite directions through tubes provided for that purpose, the tubes being arranged in staggered relation and so positioned that the air that passes through the chamber will all be affected equally by the heated tubes so as to emerge from the heater in a stream uniformly heated.

A further object of the invention is to produce a heater of a simple construction that can be readily made from sheet metal without the use of expensive tools and equipment.

The above and other objects that may become apparent as this description proceeds are attained by means of a construction and an arrangement of parts that will now be described in detail and for this purpose reference will be had to the accompanying drawing in which the invention has been illustrated in its preferred form, and in which:

Figure 1 is a section taken on line 1—1, Figure 2;

Figure 2 is a section taken on line 2—2, Figure 1; and

Figure 3 is a section taken on lines 3—3, Figures 1 and 2.

Referring now to the drawing, reference numeral 10 designates the bottom of the combustion chamber 11, and reference numeral 12 designates the top of the combustion chamber, which is also provided with sides 13 and 14 and ends 15. The combustion chamber is provided with suitable openings through which access may be had to the burner 16 that has been shown by broken lines in Figure 2. The door or opening into the combustion chamber has been shown in Figure 1 and designated by reference numeral 17.

2

There is no particular novelty in the combustion chamber or the burner, the latter being of any approved design for burning gas, if gas is the fuel or for burning liquid fuel, if such is used.

The top of the combustion chamber forms the bottom of a heat radiating and transfer chamber whose end walls have been designated by reference numeral 18, and whose top has been designated by reference numeral 19. A combustion gas receiving manifold 20 is positioned above the top plate 19 and the top of this chamber is formed by plate 21. Reference numeral 22 designates the flue for the combustion gas.

Positioned within the heat radiating chamber 15 is a radiator assembly comprising two pairs of vertically extending flues. Each pair consists of two flues of identical construction that have been designated by reference numeral 23. Each pair of flues is formed from a plate 24 that is preferably straight and a single plate bent as shown in Figure 3 from which it will be observed that each flue has inclined side walls 25 connected at 26. The joints between plate 24 and the other plate may be formed by welding, riveting or in any other suitable way. The flues have been shown as trapezoidal shape, but may be rectangular, or any other desired shape. However, it is preferable to have the inner surface, which is formed by plate 24 in the drawing, straight as shown. One flue of each pair is positioned over an opening 27 in plate 12. The flues that are in communication with the combustion chamber are not in direct communication with the manifold 20 and openings 27 are positioned on diagonally 20 located corners of the heat transfer chamber as 25 shown clearly in Figure 3. Oppositely positioned flues of the two pair are interconnected by means of tubes 28 that must be good heat conductors and for this purpose copper tubes have been 30 found very satisfactory.

A fan of the propeller type whose blades have been indicated in a general way in Figure 3 and designated by reference numeral 30 is positioned in a housing whose inclined wall has been designated by reference numeral 31. The front of the heater has an opening that has been designated by reference numeral 32 in Figure 3. When the fan is operating it produces a current of air that flows in the direction of arrows 33. It will be observed from Figure 2 that the flues 28 are arranged in staggered relation so that all of the air that passes transversely through the heat transfer chamber comes into close contact with the surface of one or more tubes. In Figure 55 2 the tubes have been shown to what is believed

to be a preferable size, but they may be larger in proportion than shown in that figure.

Referring now more particularly to Figure 3, it will be observed that the heated gases from the combustion chamber leave the latter through openings 21, they then pass upwardly through the flues that are in communication with these openings and pass through flues 28 to the corresponding vertical flue at the other end and finally leave as indicated by arrows 34 in Figure 1.

With the construction shown it is evident that all of the heated gases that leave the combustion chamber through the opening 21 at the lower righthand corner in Figure 3 pass through the tubular flues 28 in a direction towards the left, while the heated gases that enter through the opening 21 at the upper lefthand corner flow in the opposite direction. When the fan is operating and the air flows in the direction of arrow 33, the air will naturally absorb heat from flues 28 with the result that they will be cooler at the discharge end than at the intake end. Since the heated gases flow in opposite direction in the two groups, the air that comes in contact with the cooler ends of the flues in the first group will strike the next set of flues at the end where they are the hottest and as a result of this all of the air that passes through the heating chamber will have the same opportunity to absorb heat by conduction and radiation and the stream that enters the trailer or other room in which the heater is positioned will be uniformly heated at all points of its transverse area. If, for example, all of the heated gases flowed in the same direction through flues 28, the gases that contact only the cooler ends of these flues would emerge at a much lower temperature than the gases that contact the hotter ends. With the construction shown, a uniform heating of the air results which gives a higher efficiency of heat transfer and since the air from the heater is of the same temperature, it obviates the objectionable feature present in heaters of this type, in which the air is heated to different temperatures in layers perpendicular to the direction of the heating flues, is absent.

The size of the heater is, of course, immaterial so far as its patentable features are concerned. It may be stated, however, that the overall height is approximately twelve inches; its maximum width is the same, while the distance from front to back is approximately six inches, making a small compact heater for which space can readily be found in any trailer.

Having described the invention what is claimed as new is:

1. A heater for a gas such as air, comprising, means for effecting a flow of gas in a given direction, a group of substantially parallel flue gas tubes disposed laterally of the direction of flow of said gas, means for supplying the interior

of said tubes with flue gas at substantially uniform temperature and for flow therethrough in one direction, a similar group of tubes disposed downstream of the gas flow, means for supplying said similar group of tubes with flue gas at substantially uniform temperature and for flow therethrough in a direction opposite to said first group, means to supply both groups of tubes with flue gas from a common source, and means for collecting and discharging flue gas from all said tubes.

2. A device as set forth in claim 1 wherein the tubes of the groups are staggered.

3. A gas heater comprising, a housing divided by two vertically spaced, horizontal partitions, into a lower combustion chamber, a central heat transfer chamber and an upper combustion gas manifold, a radiator assembly in the heat transfer chamber, comprising, a first pair of vertical flues arranged in opposed spaced relation, a group of horizontal flues connecting the interior of the opposed flues, a second similar pair of vertical flues arranged in opposed spaced relation and spaced from the first pair, a similar group of horizontal flues connecting the interior of the second pair of opposed flues, the flues being disposed substantially along the corners of a rectangular parallelepiped, two of the flues, disposed along diagonally opposite corners of the parallelepiped, having their lower ends in communication with the combustion chamber and their upper ends closed, the other two of the flues, disposed along the other diagonally opposite corners of the parallelepiped, having their lower ends closed and their upper ends in communication with the manifold, the arrangement being such that heated gases from the combustion chamber will enter one flue of each opposed pair, pass through horizontal flues to its opposed flue and then into the manifold, whereby the hot gases will flow in opposite directions through the two groups of horizontal flues, and means for producing a flow of air transversely of the horizontal flues.

4. A heater in accordance with claim 3 wherein the tubes of the groups are staggered.
